UNITED STATES PATENT OFFICE

147,569

DESIGN FOR A BROILER BASE

Henry J. Talge, Kansas City, Mo.

Application April 4, 1946, Serial No. 128,242

Term of patent 14 years

(Cl. D44—10)

To all whom it may concern:

Be it known that I, Henry J. Talge, a citizen of the United States, residing at Kansas City, in the county of Jackson and State of Missouri, have invented a new, original, and ornamental Design for a Broiler Base, of which the following is a specification, reference being had to the accompanying drawing, forming part thereof, in which

Fig. 1 is a top plan view of a broiler base embodying my new design, and

Fig. 2 is an edge view taken from the well side of the broiler base shown in Fig. 1.

I claim:

The ornamental design for a broiler base, substantially as shown.

HENRY J. TALGE.
